UNITED STATES PATENT OFFICE.

CLARENCE S. NATHAN, OF NEW YORK, N. Y.

DESIGN FOR A CALENDAR.

SPECIFICATION forming part of Design No. 14,027, dated July 3, 1883.

Application filed November 27, 1882. Term of patent 7 years.

To all whom it may concern:

Be it known that I, CLARENCE S. NATHAN, a citizen of the United States, residing at the city of New York, in the county of New York and State of New York, have invented and produced a new and original Design for Calendars; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 This design is intended to be used for a calendar; and it consists in a configuration representing a fire-engine, having characters indicating the days of the week and month and the name of the month, which may or may 20 not have added to it a background representing buildings, and one or more or all of said buildings may be shown as on fire.

I prefer to arrange said design substantially as shown in the accompanying drawing, having the name of the month on the boiler, as at 25 *a*, the number representing the day of the month on the air-chamber *b*, and the name of the day of the week on the suction-hose *c*.

In the center of the fly-wheel *d* may be shown 30 an eyelet-hole or rivet-head, also in the center of the hub of the forward wheel, *e*, and at *f* in one of the buildings in the background.

In the rear of the fire-engine are shown several buildings, one of which is represented as

on fire. At the place marked *f*, where there 35 is an eyelet or rivet-head, I intend in some cases to represent a clock-dial, with the eyelet or rivet-head in the center.

It is evident that the configuration of this design may be varied considerably without 40 departing from the essential features thereof.

What I claim as new is—

1. A design for a calendar, consisting of a representation of a fire-engine on portions of which appear characters representing dates, 45 as shown.

2. A design for a calendar, consisting of a representation of a steam fire-engine having on its boiler the name of the month, on its air-chamber the number of the day of the month, 50 and the name of the day of the week on the suction-hose, as shown.

3. The design for a calendar herein shown, consisting of a representation of a steam fire-engine having on its boiler the name of the month, on its air-chamber the number of the day of the month, 55 on its suction-hose the name of the day of the week, and a background representing a number of houses, one or more of which are depicted as on fire, as shown and 60 described.

In testimony whereof I affix my signature in presence of two witnesses.

CLARENCE S. NATHAN.

Witnesses:

JOS. JAY PHILLIPS,
EDGAR J. NATHAN.
